UNITED STATES PATENT OFFICE.

RUDOLF LINKMEYER, OF BRUSSELS, BELGIUM.

REMOVING COPPER SALTS FROM ALKALINE LIQUORS.

No. 866,371.

Specification of Letters Patent.

Patented Sept. 17, 1907.

Application filed March 22, 1906, Serial No. 307,406.

To all whom it may concern:

Be it known that I, RUDOLF LINKMEYER, a subject of the Emperor of Germany, residing at Brussels, Belgium, have invented new and useful Improvements in the Removal of Copper Salts by Cellulose, of which the following is a specification.

In the manufacture of silk-like threads by means of a solution of cellulose in ammoniacal oxide of copper salts, when an alkaline bath is employed as precipitant a portion of the copper salts of the solution is absorbed by the alkaline lye.

In order that the process may be commercially practicable it is essential that the reagents employed, usually caustic soda, shall be economically recuperated because the precipitation of the cellulose necessitates relatively large quantities of alkalies, and the alkaline lye, owing to the copper salts that dissolves therein, assumes a blue tint which speedily becomes so deep that the attendant can no longer follow in the midst of the liquid the threads issuing from the fine openings through which the cuprammonium cellulose is forced into the alkaline lye. Although the reagent is far from being exhausted at this moment, the work cannot be proceeded with without renewing the solution unless the copper can be extracted. On the other hand the copper salts cannot be recuperated merely by ebullition of the solution and if the free alkali soda for instance is previously neutralized the process becomes too expensive, the soda being completely lost.

In accordance with the present invention the copper is extracted in a very simple manner and so that it is even able to reenter the cycle of operations directly.

The process consists in eliminating the copper salts from the alkaline lye by means of cellulose which is merely plunged into the bath. Either cotton or wood

pulp or any kind of cellulosic material will answer. The salts of copper are deposited thereon completely and at the same time a large portion of the ammonia absorbed by the alkaline lye; the cellulose assumes an increasingly blue tint while the lye becomes decolorized very rapidly and may be reemployed for the precipitation of the cupro-ammoniacal solution.

The fiber charged with copper salts may be regenerated by dissolving the copper salts and the ammonia that it contains in an appropriate acid

The direct precipitation by the alkalies is thus rendered industrial and practical, or it may be used directly for making fresh quantities of cuprammonium cellulose, after making allowance for the copper salts that have remained in the threads. The amount of copper deposited on the fiber is not sufficient for making a fresh solution of cellulose by adding only the necessary ammonia. Some of the copper contained in the previous solution having remained in the threads made out of the solution, a corresponding amount must be added to supplement that which has been removed by the fiber in order to make up for the deficiency.

What I claim as my invention and desire to secure by Letters Patent is:

In the manufacture of artificial silk from cuprammonium cellulose, the process of removing copper from the residual caustic alkaline liquors which consists in immersing bundles of vegetable fibers therein until the copper has deposited thereon and removing them, together with the adhering copper salts.

In testimony whereof I have affixed my signature in presence of two subscribing witnesses.

RUDOLF LINKMEYER.
